UNITED STATES PATENT OFFICE.

EDWARD GRUENINGER, OF CINCINNATI, OHIO, ASSIGNOR OF ONE-HALF TO FRED J. TREUHEIT AND GUY E. FORSTER, OF CINCINNATI, OHIO.

AUTOMATIC GAS-VALVE FOR DOWN-SPOUTS.

1,103,043.

Specification of Letters Patent.

Patented July 14, 1914.

Application filed September 29, 1913. Serial No. 792,385.

To all whom it may concern:

Be it known that I, EDWARD GRUENINGER, a citizen of the United States, residing at Cincinnati, in the county of Hamilton and 5 State of Ohio, have invented certain new and useful Improvements in Automatic Gas-Valves for Down-Spouts, of which the following is a specification.

It is the object of my invention to provide 10 a novel automatic gas valve for down-spouts, such as down-spouts leading from the roofs of houses into sewer systems.

It has been found in practice that the 15 sewer gases have a corroding effect upon the down-spouts, and it is the object of my invention to avoid passage of these gases through the down-spouts.

It is the object of my invention further to provide 20 novel means for deflecting the sewer gas into the atmosphere while permitting free passage of the water through the down-spout; and, further, to provide novel means whereby the seat of the valve is protected from corrosion.

25 The invention will be further readily understood from the following description and claims, and from the drawings, in which latter:

Figure 1 is a perspective view of my improved 30 device with a side of the casing partly broken away. Fig. 2 is a plan view of the same. Fig. 3 is a central vertical section of the same on the line 3—3 of Fig. 2. Fig. 4 is a detail of the valve in section 35 on the line 4—4 of Fig. 3. Fig. 5 is a horizontal section on a line corresponding to the line 5—5 of Fig. 3. Fig. 6 is a horizontal cross-section on a line corresponding to the line 6—6 of Fig. 3; and, Fig. 7 is a plan 40 view of the valve.

11 represents the casing of my improved device, which is shown as a casing which tapers downwardly, being preferably straight at one side and slanting at its other 45 side, and provided with rounded end walls and comparatively flat side walls, and formed with a rounded lower end.

12 is an inlet-pipe suitably secured in the top 13 of the casing. This top, adjacent to 50 the inlet-pipe is preferably imperforate, as shown at 14, for protecting the valve parts hereinafter described from the rain, the balance of said top being preferably grated for forming a grated opening, as shown at 15, 55 the grating preventing leaves and other in-

terfering objects being introduced into the casing. The down-spout 16 is arranged to be received in the inlet-pipe.

The lower end of the casing is in the form of a collar 21 forming an outlet for the casing and is received in a suitable drain pipe 22 which has connection with the sewer. The water inlet is shown directly above the water outlet at the straight side of the casing. 60

I provide novel means for preventing corrosive gases from entering the down-spout and inlet-pipe and for easy escape of said gases into the atmosphere.

The lower end of the inlet-pipe is formed 70 tapering for forming a downwardly slanting valve-seat 23 with which a valve 24 coacts. This valve is shown as a pipe section, suitably cut for shaping its lower end tapering, forming a lip 25. The bore 26 of its 75 upper end 27 forms a gas-passage, presented toward the grated opening 15. The valve is so hinged as to normally hang against the valve-seat, as by a hinge comprising a U-shaped bracket 28, secured adjacent to the 80 upper end of the valve and received through eyes 29 secured to the inlet-pipe adjacent to the upper end of the tapering portion of the latter.

The portion of the valve which coacts 85 with the valve-seat is in the form of a lip which tapers downwardly and is cross-sectionally rounded for presenting a bulged downwardly slanting surface 30 to the inlet-pipe and a channeled upwardly slanting 90 surface 31 to the outlet opening communicating with the gas-passage 26, so that water descending from the inlet-pipe may be readily shed from said valve and gas passing through said outlet opening may be readily 95 directed toward said grated opening.

The parts are so related as to automatically force the valve into coaction with its valve-seat by gravity. Thus the cylindrical portion 27 of the valve-pipe forms a counter-weight. The axis of the cylindrical portion, when the valve is closed, is substantially 100 at an acute angle to the axis of the inlet-pipe. The lip 25 is substantially a continuation of the cylindrical counter-weight 105 portion.

For protecting the valve-seat I provide the lip 25 with a peripheral flange 32 arranged to be received below the valve-seat and preferably coacting with the walls of 110

the casing adjacent to said valve-seat for forming a protecting chamber 33 at the said valve-seat, the inlet-pipe and the valve-seat being in said chamber, the said flange slanting 5 slightly downwardly toward its outer edges for forming a gas deflecting surface at its bottom merging into the lower face of the lip.

In use, the gases rising in the drain-pipe 10 22 will strike the gas deflecting lower surface on the flange and the gas deflecting surface 31 on the valve, the said surfaces acting to deflect the said gases through the gas passage 26 and out through the grated 15 opening 15 in the top of the casing. Water passing down the pipe will strike the upper surface of the lip of the valve, being quickly drained past the peripheral flange thereof, and causing swinging of the valve on its 20 hinge away from the seat 23 on the inlet-pipe against the action of the counter-weight portion 27, the valve immediately swinging back into place.

Having thus fully described my invention, 25 what I claim as new and desire to secure by Letters Patent, is:

1. In an automatic gas valve for down-spouts, the combination of a casing, an inlet-pipe arranged in said casing, said inlet-pipe 30 having a downwardly tapering lower end which forms a valve-seat, and a valve in said casing for said valve-seat having a downwardly tapering lip provided with a transversely bulging downwardly sloping 35 water deflecting upper surface coacting with said valve-seat and a transversely channeled downwardly sloping gas deflecting lower surface, said valve being counterweighted for normally urging said lip toward said 40 valve-seat.

2. In an automatic gas valve for down-

spouts, the combination of a casing, a cover therefor, an inlet-pipe arranged in said casing, said inlet-pipe provided with a downwardly slanting lower end forming a valve-seat, and a valve-pipe whose upper end is pivoted adjacent the upper end of said slanting lower end of said inlet-pipe, said valve-pipe having a tapering lower end for forming a lip coacting with said valve-seat, 45 said lip provided with an outwardly extending peripheral flange below said valve-seat, said cover being at one end thereof imperforate above said valve-seat, lip and pivotal connection and formed as a grated opening 50 at the other end of said cover, and the bore of said valve-pipe opening upwardly below said grated opening, substantially as described.

3. In a device of the character described, 60 the combination of a case, an inlet-pipe provided with a valve-seat within said case, and a valve-pipe pivoted within said case to said inlet-pipe and arranged to contact said seat, said valve-pipe provided with a flange ar- 65 ranged to coact with the walls of said case for forming a protective chamber within said case above said flange for protecting said valve-seat on said inlet-pipe, said valve-pipe having an upper end opening up- 70 wardly above said seat, and said case provided with a grated opening above said upper end of said valve-pipe, substantially for the purpose set forth.

In testimony whereof, I have hereunto 75 signed my name in the presence of two subscribing witnesses.

EDWARD GRUENINGER.
